FLAME STABILIZING ATTACHMENT FOR
ORCHARD HEATERS

Willis L. Scheu, Ontario, Calif., assignor to Scheu
Products Company Limited, Ontario, Calif., a
corporation of California

Application September 19, 1932, Serial No. 633,754

12 Claims. (Cl. 158—91)

This invention relates to an attachment for liquid-fuel orchard heaters, and particularly to an attachment for such heaters which will increase the operating efficiency and improve the 5 operating characteristics of liquid-fuel orchard heaters of a certain general type.

The device of the present invention is adapted for use on an orchard heater of the type comprising a liquid-fuel receptacle having a closely-fitting cover provided with vaporizing-flame air-admitting means having a closely-fitting regulating plate, and vapor-outlet means in said cover provided with a stack communicating therewith. When used with a heater of the above 10 type, the device of the present invention serves to improve the operating characteristics of such a heater by causing the vaporizing-flame to be stabilized and persist in the vicinity of the air-admitting means, and thus obtain more stable 15 operation of the heater.

The above-mentioned type of heater is normally adapted for relatively slow burning, under moderate and steady draft conditions, and many attempts have been made to modify this type of 20 heater to obtain more efficient fuel combustion and more smokeless operation, but, until the advent of the present invention, these attempts were unsuccessful due to the fact that attempted changes in stack design for the purpose of providing better combustion tended to produce an 25 increased draft, and thus caused the generating or vaporizing flame to "jump" into the stack, extinguishing the heater. This tendency of the vaporizing-flame to "jump" is particularly noticeable when a stack of a type which produces a "puffing" or pulsating combustion is used on 30 a heater of the type above described.

The principal object of the present invention is, therefore, to provide a flame stabilizing attachment for a liquid-fuel orchard heater adapted 35 to cause the vaporizing-flame to persist in the vicinity of the air-admitting opening, in spite of high draft, or of fluctuations in draft produced by such puffing or pulsating combustion, whereby 40 "jumping" and consequent extinguishing of the heater is prevented.

A further object of the invention is to provide 45 an attachment for a liquid fuel orchard heater adapted to cause the vaporizing-flame to persist in the vicinity of the air-admitting opening as and for the reasons above set forth, whereby additional air is admitted to the interior of the fuel receptacle in such manner as to disturb the inward flow of air through said air-admitting open- 50 ing.

The device of the present invention is particularly adapted for installation on an orchard heater having air-admitting means of the type which comprises a regulating plate having one or more openings therein which are adapted to be placed in or out of registration with a suitable opening in the heater cover, whereby the amount of air admitted to the interior of the heater may be regulated within the desired limits.

In its broadest scope, the present invention 10 contemplates the provision of a device adapted to be attached to an orchard heater in such manner and in such position that additional air is admitted to the heater adjacent the point of admission of air for the support of the vaporizing-flame, and may comprise a device adapted to admit additional air immediately adjacent said point, or may comprise a device adapted to admit additional air at a point somewhat removed 15 from said point, as for example at the edge of the heater cover, or may comprise a device adapted to admit additional air at both of said points.

Thus, the device may comprise a spacing member adapted to be placed between the upper wall 20 of the heater cover and the aforementioned regulating plate, at a point adjacent the air-admitting opening, whereby the said regulating plate is spaced from the surface of the heater cover and air is admitted to the interior of the heater by passing under the regulating plate and thence 25 through the air-admitting opening, or, the device may comprise a spacing member adapted to be inserted between the upper edge of the fuel receptacle and the heater cover at the side thereof 30 adjacent the air-admitting means so that said heater cover is spaced from said upper edge of the fuel receptacle and an air space is provided 35 therebetween for admission of additional air to the interior of said heater adjacent the position of the air-admitting means, or, further, the device may advantageously comprise a construction embodying both of the above mentioned spacing members, whereby additional air is admitted to 40 the interior of said heater at both of said positions.

The generating or vaporizing flame which provides for vaporization of the liquid fuel in the heater is maintained by the inward flow of air through the aforesaid air-admitting means, and admission of additional air in the manner above 45 specified obtains a more stable operation of this generating flame, contributing in a material manner to the operation of the heater.

The device of the present invention may advantageously comprise one adapted to function in the 50 55

manner above set forth, and provided in addition with suitable wick-supporting means, whereby the wick is supported in a particularly advantageous position with respect to the air-admitting means.

The accompanying drawings illustrate various embodiments of my invention, and referring thereto:

Fig. 1 is a partly broken away side elevation of a liquid fuel heater provided with a device of the present invention;

Fig. 2 is a plan view of said heater;

Fig. 3 is an enlarged view of a portion of Fig. 2, showing the air-admitting means, with a portion 15 of the regulating plate of said air-admitting means broken away;

Fig. 4 is an enlarged sectional detail taken on line 4-4 in Fig. 1;

Fig. 5 is an enlarged sectional view of the form 20 of device shown in Fig. 1, all parts thereof except those adjacent the air-admitting means being broken away;

Fig. 6 is a sectional view taken on line 6-6 in Fig. 5;

Fig. 7 is a perspective view of a preferred form 25 of the present device;

Figs. 8 to 11 are views corresponding to Fig. 5, showing alternative modifications of the device of the present invention;

Fig. 12 is a view corresponding to that shown 30 in Fig. 3, showing an alternative form of device of the present invention;

Fig. 13 is a sectional view thereof, taken on line 13-13 in Fig. 12.

Figs. 1 to 4 show a liquid fuel heater of the 35 type to which the device of the present invention is particularly adaptable, and referring thereto, said heater is shown as comprising a fuel receptacle 1, formed as a rectangular pan having a side wall 1a provided with a beaded upper edge 2, and a cover 3 provided with a depending flange 4 which is customarily provided with a groove 5 adapted to receive the beaded upper edge 2, as clearly shown in Fig. 1. The cover 3 is customarily tapered inwardly and upwardly to a centrally disposed vapor outlet adapted to receive a stack 6. The stack 6 is shown as provided with a plurality of louvres 7 which provide for admission of combustion air to the interior thereof 45 during operation of the heater, and may also be provided with a cover 8. The heater cover 3 is also provided with air-admitting means indicated at 9 and a fuel-charging aperture 11 provided with a removable cap 12.

The air-admitting means may comprise an 50 opening in the cover proper, such as a semi-circular slot 13, and a rotatable regulating plate 14 provided with a plurality of air-admitting holes 15 preferably set on the same radius as that of the slot 13. The plate 14 is rotatably supported at the center of curvature of the slot 13 in any suitable manner, as by means of a rivet 16, and may be provided with a projection 15a to allow of easy adjustment of said plate. Upon rotation of the plate 14, one or more of the holes 15 may be brought into registration with the slot 13 and a greater or lesser amount of air admitted to the interior of the heater, as desired.

The device of the present invention may be 70 formed as a single piece of metal, such as shown in perspective at 21 in Fig. 7 for example, provided with a bent-over portion 21a at one end, an intermediate portion 21b, a cover-engaging lip 21c at the other end, and a depending wick-supporting portion 21d adjacent said lip. The por-

tion 21a is joined to the intermediate portion 21b by a curved portion 21e of approximately the same curvature as that of the beaded upper edge 2 of the heater to which the device is to be attached so that said device will receive said bead within the curved portion 21e after the manner shown particularly in Figs. 1 and 5.

The device 21 is adapted to be attached to a heater of the type above described in the following manner: With the cover 3 lifted clear of the upper edge 2 of the receptacle 1, the device is secured to the cover by inserting the cover-engaging lip 21c into the slot 13 and forcing said lip between the cover and the plate 14 into a position such as shown in Figs. 1, 3 and 5, with the curved portion 21e tucked into the groove 5. The cover is then lowered into position on the receptacle, and the curved portion 21e will then come into engagement with the bead 2, as shown. With the device in this position, it will be seen by referring, for example, to Fig. 4, that the regulating plate 14 is lifted from the cover 3, leaving a space 14a at either side of the element 21.

In this position, the portion 21e of the device will engage the bead 2 and the cover 3 will be supported in spaced relation to said bead, leaving a space 2a (as shown, for example, in Fig. 6) between the cover portion 5 and the bead 2. The wick-support 21d is thus disposed in position between the edge of the cover 3 and the air admitting slot 13, and a suitable wick 22 may be held in that position, as shown in Fig. 1.

The above-described form of orchard heater is adapted to be filled with a suitable liquid fuel to any desired level within the receptacle 1, a wick 35 is hung on the wick support 21d in position to be wetted by the liquid fuel within the heater, and burning igniting fuel is poured through one of the air-admitting openings 15 and through the slot 13 onto the surface of the fuel in the heater. 40 This burning igniting fuel will burn within the heater and heat the fuel sufficiently to cause production of combustible vapors, after which the combustion within the receptacle portion of the heater will be confined to a generating-flame at 45 the point or points of air-admission and the main combustion of the vaporized fuel will take place within and above the stack 6. The generating-flame will cause a continuous liberation of combustible vapors from the liquid fuel within the 50 heater, and supply such vapors for the main combustion.

The device of the present invention is adapted to allow additional air to be admitted to the interior of the orchard heater in such position with 55 respect to the generating-flame air-admitting means that said additionally admitted air influences and disturbs the air stream passing through said air-admitting means. When this device is used with a heater of the general type above described, the vaporizing-flame, or generating-flame, is caused to persist in the vicinity of the air-admitting opening, and stable operation 60 of the heater is established under substantially all draft conditions.

The device of the present invention is of particularly advantageous use on a heater provided with a stack which induces a relatively large or powerful draft, which ordinarily causes the vaporizing-flame to be sucked up the draft stack 70 and thus extinguished. The above-described form of heater is normally designed to operate with a medium-strength draft, and in this case, the vaporizing-flame is able to persist in its proper position. When, however, a stack of a 75

type adapted to produce a strong draft is used, such as a form of stack of the type shown in Fig. 1, the vaporizing-flame will tend to "jump" into the stack and be extinguished, and it is under such conditions that the device of the present invention will so alter the nature or form of the stream of admitted air that the vaporizing flame persists in its proper place within the base portion of the heater.

10 In Figs. 8 to 13, I have shown modifications of the device of the present invention, and referring thereto, Fig. 8 shows a device 23 comprising a cover-engaging lip 23a and a wick-support 23b, said cover-engaging lip 23a being adapted for insertion between a heater cover 3' and a regulating-plate 14', said device extending through an air-admitting slot 13' in said cover 3', after the manner shown in Figs. 1 to 4, and said regulating-plate being provided with one or more air-inlet openings 15'. This form of device is adapted to admit additional air to the interior of the heater in the vicinity of the main air-admitting openings, and does not provide for admission of air between the cover and the upper edge of the 25 side wall of the receptacle 1'.

The form of device shown in Fig. 9 may comprise a metal strip 24 provided with a cover-engaging lip 24a, a wick-support 24b extended inwardly of the heater so as to be disposed between the air-admitting opening 13'' and the vapor-outlet, not shown, whereby the wick 25 may be supported at a point inwardly removed from said air-admitting opening. This form of device may be formed and supplied to the user substantially in the shape shown in Fig. 10 in which the end of the device shown at the left side is made substantially straight, as at 24c, and this straight end-portion may be inserted through the opening 13'', forced between the cover 3'' and the regulating-plate 14'' until the cover-engaging lip 24a engages the edge of the opening 13'', the end-portion 24c being then bent over the edge of the cover 3'' as shown at 24d.

45 The form of device shown in Fig. 11 may comprise a metal strip 26 provided with a wick-support portion 26a and a curved portion 26b adapted to fit over the bead 2 of the heater base portion 1, and be held in such position by the groove 5 of the cover 3. This form of device provides for admission of air along the cover edge, in the same manner as does the device shown at 21 in Figs. 1 to 6, but does not provide for admission of additional air under the air-admitting means regulator plate.

55 The form of device shown in Figs. 12 and 13 may comprise a strip of metal 27 inserted between the cover 3 and a regulating plate 14 and having its ends bent up and over to clamp the strip in position, one end 27a of said strip being passed through an opening 15 in the regulating plate and then bent over onto the regulating plate, and the other end 27b of said strip being bent up and over the outside edge of said plate. This 60 form of device provides only for spacing the regulating plate from the cover, after the fashion of the form of device shown in Fig. 8.

65 It will be seen that the device of the present invention is particularly characterized by its simplicity, and it is apparent that numerous modifications may be made in the specific mode and form of construction thereof. Accordingly, I do not wish to be limited to the exact forms of device herein delineated and described, but rather to the 70 scope of the invention as set forth in the accom-

panying claims forming a part of this specification.

I claim:

1. In combination with a liquid-fuel orchard heater having a receptacle provided with a side wall, a removable cover engaging the upper edge of said side wall and provided with an air-admitting opening located adjacent one edge thereof, a combustion stack communicating with the interior of said receptacle, and a regulating plate 10 adjustably mounted on said cover and provided with aperture means movable into and out of position of registration with said air-admitting opening to provide for admission of air to maintain a generating flame within said receptacle 15 adjacent said opening, said side wall and said regulating plate constituting enclosing members normally in substantially tight engagement with said cover so as to cause the interior of said receptacle to be substantially enclosed from the 20 atmosphere except through said aperture means; a flame stabilizing device secured to said heater and having a portion extending between said cover and one of said enclosing members so as to separate said one member from said cover and 25 provide for admission of additional air to the interior of said receptacle between said cover and said one member, at a point adjacent the position of said generating flame.

2. The invention set forth in claim 1; said device also having wick support means disposed adjacent the position of said generating flame.

3. The invention set forth in claim 1; said device also having a portion extending between and separating the cover and the other of said members 35 to provide for admission of additional air therebetween.

4. The invention set forth in claim 1; said device being provided, in addition, with a portion 40 extending between and separating the cover and the other of said members to provide for admission of additional air therebetween, and wick support means disposed adjacent the position of said generating flame.

5. In combination with a liquid-fuel orchard 45 heater having a receptacle provided with a side wall, a removable cover engaging the upper edge of said side wall and provided with an air-admitting opening located adjacent one edge thereof, a combustion stack communicating with the interior of said receptacle, and a regulating plate 50 adjustably mounted on said cover and provided with aperture means movable into and out of position of registration with said air-admitting opening to provide for admission of air to maintain a generating flame within said receptacle adjacent said opening, said regulating plate being normally in substantially tight engagement with said cover so as to cause the interior of said receptacle to be substantially enclosed from the atmosphere except through said air-admitting opening; a flame stabilizing device secured to said heater and having a portion extending between said cover and said regulating plate so as to separate said cover and said plate and provide for admission of 55 additional air to the interior of said receptacle between said cover and said plate, at a point adjacent the position of said generating flame.

6. The invention set forth in claim 5; said device being provided with means for securing the 60 same to said cover.

7. The invention set forth in claim 5; said device being provided with means for securing the same to said regulating plate.

8. The invention set forth in claim 5; said de- 75

vice also having wick support means disposed adjacent the position of said generating flame.

9. In combination with a liquid-fuel orchard heater having a receptacle provided with a side wall, a removable cover engaging the upper edge of said side wall and provided with an air-admitting opening located adjacent one edge thereof, a combustion stack communicating with the interior of said receptacle, and a regulating plate 10 adjustably mounted on said cover and provided with aperture means movable into and out of position of registration with said air-admitting opening to provide for admission of air to maintain a generating flame within said receptacle 15 adjacent said opening, said side wall being normally in substantially tight engagement with said cover so as to cause said receptacle to be substantially enclosed from the atmosphere except through said air-admitting opening; a flame 20 stabilizing device secured to said heater and having a portion extending between said cover and the upper edge of said side wall so as to separate said cover from said side wall and provide for admission of additional air to the interior of said receptacle between said upper edge 25 of said side wall and said cover, at a point adjacent the position of said generating flame.

10. The invention set forth in claim 9; said device also having wick support means disposed 30 adjacent the position of said generating flame.

11. In combination with a liquid fuel orchard heater having a receptacle provided with a side wall, a removable cover engaging the upper edge of said side wall and provided with an air-admitting 35 opening located adjacent one edge thereof, and a regulating plate adjustably mounted on said cover and provided with aperture means movable into and out of position of registration with said air-admitting opening to provide for admission of air to maintain a generating flame within said receptacle adjacent said opening, said side wall and said regulating plate being normal- 40

ly in substantially tight engagement with said cover so as to cause the interior of said receptacle to be substantially enclosed from the atmosphere except through said air-admitting opening; a flame stabilizing device secured to said heater and having a portion extending between said cover and said regulating plate so as to separate said cover and said plate and provide for admission of additional air to the interior of said receptacle between said cover and said plate at a point adjacent the position of said generating flame, 10 said device also having a portion extending between said cover and said side wall so as to separate said cover and said side wall and provide for admission of additional air therebetween. 15

12. In combination with a liquid-fuel orchard heater having a receptacle provided with a side wall, a removable cover engaging the upper edge of said side wall and provided with an air-admitting opening located adjacent one edge thereof, 20 and a regulating plate adjustably mounted on said cover and provided with aperture means movable into and out of position of registration with said air-admitting opening to provide for admission of air to maintain a generating flame within said receptacle adjacent said opening, said side wall and said regulating plate constituting enclosing members normally in substantially tight engagement with said cover so as to cause the interior of said receptacle to be substantially enclosed from the atmosphere except through said aperture means; a flame stabilizing device secured to said heater, adjacent said air-admitting opening and having a portion extending between said cover and one of said enclosing members so as to 30 separate said one member from said cover and provide for admission of additional air to the interior of said receptacle between said cover and said one member at a position to influence and disturb the air stream passing through said air-admitting opening. 35

WILLIS L. SCHEU.
